UNITED STATES PATENT OFFICE.

ADIN U. KERNS, OF ALTOONA, PENNSYLVANIA.

HOPPER CAR.

Application filed February 1, 1927. Serial No. 165,078.

My invention relates to hopper cars with hinged drop doors.

As hopper cars have heretofore been constructed the drop doors of the hoppers have been hinged to and close upon the ends of sheets forming the outlet orifice of the hoppers or upon reinforcing parts secured to such sheet ends but not in themselves forming a separate door frame. In such used construction difficulty has been found in properly fitting the doors to the openings and in keeping them properly aligned to receive a sufficiently tight closure. The object of my invention is to provide a hopper door frame of firm and complete structure which can be constructed as a complete article of manufacture and secured to the plate ends forming the hopper openings after it is finished. My hopper door frame is made up of an upper member, preferably a casting to which the door hinges are attached, and of side and bottom members preferably made up of a Z bar bent into U shape and firmly attached at its ends to the top member. The top, bottom and side members however constructed are firmly secured together as a frame and are provided with rivet flanges for attaching them to the plate ends forming the mouth of the hopper.

Car construction necessitates that twin hoppers should be used and in forming my door frames I secure the frames for the twin hoppers together by means of a beam firmly secured to the lower member of the twin frames and by preference I also secure the lower edges of the twin doors together by a beam.

The nature of my improvements will be best understood as described in connection with the drawings, which illustrate a portion of a hopper car having my improved drop door frames secured to the ends of the twin hoppers and in which

Figure 1 is a perspective view showing the twin hopper openings to which are secured the drop door frames, the doors being shown as partly open.

Figure 2 is a front elevation of the twin door frames with the drop doors secured in place and the frames secured together.

Figure 3 is an end elevation of the structure shown in Fig. 2.

Figure 4 a cross section on the line 4—4 of Fig. 2.

Figure 5 a section on the line 5—5 of Fig. 2, and

Figure 6 a section on the line 6—6 of Fig. 2.

A indicates the top member of my swing door frame. As shown, and as preferably constructed it is formed of a casting having a riveted flange A¹, an outwardly extending stiffening flange A² with which are preferably connected the brackets A⁴, A⁴ which form supports for the hinge pins indicated at F, which extend across the space indicated at a³ lying between each pair of brackets A⁴, A⁴. The member A is also provided with a downwardly extending ledge indicated at A⁵ to form a seat for the top edge of the door D. As shown, the member A is also provided with brackets A⁶ located at its ends and to which are attached the side members B, B, which by preference I form integral with the bottom member B¹; the members having a general U form and being preferably made from a rolled bar of Z section as shown, the intermediate flange b² forming a seat for the door, the flange b fitting around the edges of the door when closed and the flange b¹ forming a riveting flange by which the side and bottom members are attached to the ends of the plates forming the hopper.

By preference the two frames adapted for use on the twin hoppers of the car are firmly secured together by a beam, as indicated at C, a rolled L beam being conveniently used for this purpose. D, D indicates the doors, which are formed of sheet metal with outwardly turned flanges d. E, E indicate the hinge strips riveted to the doors and hinged on the pivot pins F. By preference, the twin doors D, D are firmly secured together by a connecting beam, as shown. Each door has riveted to its lower portion a stool, indicated at G, and these stools are connected together by a U beam H.

I indicates the sloping bottom plate of one of the hoppers. J, Fig. 4, indicates the end of the top plate forming one of the hoppers. K, K are the side sheets making up the hoppers in connection with the top and bottom plates. L, L¹ indicate rivets holding the side members to the upper member. M indicate the rivets by which the upper mem-

ber of the frame is attached to the plate J and M¹ indicate rivets attaching the flange b¹ to the plates K, K. M² are the rivets attaching the flange b¹ to the plate I.

5 It will be seen that my drop door frames are complete articles of manufacture, having all necessary strength and permanency of construction apart from their attachment to the plate ends of the hoppers. My frames 10 can be attached either to new or old cars and would naturally be of a strength which would usually outlast the plates to which they are attached. My frames afford a secure closure in connection with the doors 15 hinged to them and which doors by my construction may be relied upon to afford a secure closure for the hoppers under all ordinary conditions of use.

Having now described my invention, what 20 I claim as new and desire to secure by Letters Patent is:

1. As an article of manufacture a pair of drop door frames for a hopper car each comprising an upper member provided with 25 hinge pin supports, and side and lower members firmly secured to said upper member and forming with it a complete door frame, said members having rivet flanges alined to contact with the plates forming the 30 delivery hopper of a car, in combination with a beam secured to the lower members

of the frames and holding them in spaced and alined position to fit in twin delivery hoppers of a car.

2. As an article of manufacture a pair of 35 drop door frames for a hopper car each comprising an upper member provided with hinge pin supports, and side and lower members firmly secured to said upper member and forming with it a complete door 40 frame, said members having rivet flanges alined to contact with the plates forming the delivery hopper of a car in combination with a beam secured to the lower members 45 of the frames and holding them in spaced and aligned position to fit in twin delivery hoppers of a car, a pair of doors hinged on to each door frame and a beam secured to the lower portion of the doors holding them in spaced relation to each other and to the 50 door frames.

3. A drop door frame for a hopper car comprising an upper member provided with hinge pin supports, a seat ledge for the upper edge of a door and a rivet flange for attachment to the cross ridge sheet of the delivery hopper of a car in combination with 55 side and bottom members formed of a Z shaped rolled section of yoke shape firmly secured to the upper member at its ends.
